Primary Examiner — Rachel A. Voorhies*Assistant Examiner* — Benjamin D. Wannemacher(74) *Attorney, Agent, or Firm* — Guice Patents PLLC(57) **CLAIM**

The ornamental design for a driver of a wrench, as shown and described.

DESCRIPTION

FIG. 1 is a perspective view of the driver;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a drawing illustrating that the driver is disposed in a head of a wrench.

The dash-dash broken lines in FIG. 1-7 are for the purpose of illustrating portions of the driver of a wrench that form no part of the claimed design. The short dash-dash broken lines in FIG. 8 are for the purpose of illustrating portions of the driver of a wrench that form no part of the claimed design. The dash-dash broken lines in FIG. 8 illustrate the environment of the claimed design and forms no part thereof.

1 Claim, 5 Drawing Sheets(56)
